(57) **CLAIM**

The ornamental design for a swivel loop for exercise bar, as shown and described.

DESCRIPTION

FIG. 1 is a front perspective view of the swivel loop for exercise bar of the present invention;

FIG. 2 is a back perspective view of the swivel loop for exercise bar shown in FIG. 1;

FIG. 3 is a back view of the swivel loop for exercise bar shown in FIG. 1; and

FIG. 4 is a right side view of the swivel loop for exercise bar shown in FIG. 1;

FIG. 5 is a front view of the swivel loop for exercise bar shown in FIG. 1;

FIG. 6 is a left side view of the swivel loop for exercise bar shown in FIG. 1;

FIG. 7 is a top view of the swivel loop for exercise bar shown in FIG. 1; and,

FIG. 8 is a bottom view of the swivel loop for exercise bar shown in FIG. 1.

The broken lines shown in the figures are for the purpose of illustrating portions of the swivel loop for exercise bar, which form no part of the claimed design.
